UNITED STATES PATENT OFFICE.

MICHAEL J. DEL GREGO, OF AKRON, OHIO.

DESIGN FOR AN ELASTIC VEHICLE-TIRE.

48,244.

Specification for Design.

Patented Dec. 7, 1915.

Application filed June 14, 1915. Serial No. 34,126. Term of patent 14 years.

To all whom it may concern:

Be it known that I, MICHAEL J. DEL GREGO, a citizen of the United States, and a resident of Akron, in the county of Summit and State of Ohio, have invented a new, original, and ornamental Design for Elastic Vehicle-Tires, of which the following is a specification, reference being had to the accompanying drawing, forming part thereof.

The figure is a perspective view of an elastic vehicle tire showing my new design.

I claim:

The ornamental design for an elastic vehicle tire, as shown.

MICHAEL J. DEL GREGO.
